C. P. GIFFORD.
ICE CREEPER.
FILED JAN. 6, 1922.

Inventor.
Cyrus P. Gifford
By J. F. M. Stanger
Attest.

UNITED STATES PATENT OFFICE.

CYRUS P. GIFFORD, OF ERIE, PENNSYLVANIA.

ICE CREEPER.

Application filed January 6, 1922. Serial No. 527,346.

To all whom it may concern:

Be it known that I, CYRUS P. GIFFORD, a citizen of the United States, residing at Erie, in the county of Erie and State of Pennsylvania, have invented certain new and useful Improvements in Ice Creepers; and I do hereby declare the following to be a full, clear, and exact description of the invention, such as will enable others skilled in the art 10 to which it appertains to make and use the same, reference being had to the accompanying drawings, and to the letters of reference marked thereon, forming part of this specification.

15 My invention relates to ice-creepers, and the object thereof is to provide a device by means of which suitable spurs or creepers can be secured under the heels or rubber over-shoes without the aid of screws or rivets, and 20 which can be quickly placed on the over-shoe or removed therefrom, as desired.

The features of my invention are hereinafter fully explained and pointed out and are illustrated in the accompanying drawings in which:

Figure 1, is a side elevation of a rubber over-shoe having an ice-creeper thereon embodying my invention.

Figure 2, is a plan view of the underside 30 of the same.

Figure 3, is a section of the creeper mechanism removed from the shoe, on the line $x-x$ in Fig. 2.

Figure 4, is a front end view of my improved creeper mechanism.

Figure 5, is a plan view of a modified construction of my creeper mechanism.

In these drawings A indicates the sole portion of the heel of an over-shoe, which, 40 as is well known, projects in a sort of bead around the heel. B is a middle plate provided with upturned ears B' at opposite sides thereof. C indicates a wire secured in the upper ends of the ears B' so that said wire 45 will fit around the heel of the over-shoe and engage the upper edge of the sole A.

In Fig. 3 is illustrated the manner in which the ears B' are bent around the wire C, viz:—from the outside of the wire over 50 and down and under, inside of the wire, so that the wire C is held in engagement with the bead of the heel sole A, around the entire perimeter of the heel of the over-shoe. F indicates a bar which is placed transverse 55 of the over-shoe in front of the heel sole A, and the ends f thereof are upturned and

hooked, so as to receive the ends of the wire C and hold the same inward against the body of the over-shoe and upon the heel sole A.

To prevent bars F from moving forwardly, the ends c of the wire C are turned upwardly as shown in Fig. 1 and Fig 4. I also provide a strap G which is secured to the bar F and extends backwardly under the heel of the shoe and is secured to the plate B by means of a stud-pin g which extends through the hole g' in the strap G. Upon the under side of the plate B is secured a plate H, the edges H' of which are turned downwardly and at an angle to each other so that said edges form cleats which bite into the snow and ice. The plate H is formed therein and a guideway h through which the strap G slidably passes.

In Fig. 5 I show an alternative view in which the plate B is in two parts—B² and B³, which are secured together by means of the spring b; each of the parts B² being provided with upturned ears B' as in Fig. 1.

The plate H is permanently secured to one of the parts B², and the other part B² is provided with a slot b', in which slot a rivet b² operates to hold the part B² upon the cleat plate H. The other features remain the same as in Figs. 1 and 2. The operation of the construction shown in Fig. 5 permits the parts B² and the ears B' thereon, to move inwardly when the ends c of the wire C are pressed toward each other in securing the creeper upon the over-shoe so that the upper beaded ends of the ears B' will be securely clamped upon the bead A of the heel sole of the over-shoe.

Having thus fully shown and described my invention so as to enable others to utilize the same, I do not desire to be limited to the exact mechanism shown and described, as many modifications can be made therein without departing from the scope of my invention; therefore what I claim as new and desire to secure by Letters Patent is:—

1. In a device of the class described, a cleat plate, upwardly extending ears on opposite edges thereof, a return-bend wire secured in said ears, a transverse bar engaging the free ends of said wire, a rearwardly extending bar secured to the intermediate portion of said transverse bar, a guide-way plate secured on said cleat plate embracing said rearwardly extending bar, and means to adjust the length of said last mentioned

bar between said guide-way plate and said transverse bar.

2. In a device of the class described, a cleat plate, upwardly extending ears on opposite edges thereof, a return-bend wire secured in said ears, a transverse bar engaging the free ends of said wire, a rearwardly extending bar having holes therethrough secured to the intermediate portion of said transverse bar, means on said cleat plate to slidably engage said rearwardly extending bar, and a stud on said cleat plate adapted to en-

gage one of the holes in said rearwardly extending bar.

3. In a device of the class described, a cleat plate, a pair of plates laterally movable with relation to each other and secured on said cleat plate, upturned ears on said last mentioned plates, a return-bend wire secured in said ears, and means to clamp said wire and ears around an over-shoe heel.

In testimony whereof I affix my signature.

CYRUS P. GIFFORD.
